UNITED STATES PATENT OFFICE

JOHN WEBER, OF SCHENECTADY, NEW YORK, ASSIGNOR TO WEBER ELECTRIC COMPANY, OF SCHENECTADY, NEW YORK, A CORPORATION OF NEW YORK

ELECTRIC LAMP SOCKET CASING

Application filed July 30, 1929. Serial No. 382,259.

This invention relates to new and useful improvements in electric lamp socket casings, which consist broadly of a cap usually adapted to be connected with an electrical conductor conduit, and a shell detachably connected with the cap and adapted to house a lamp socket with its well known adjuncts, such as an insulating block carrying the usual contacts, terminals, switch and switch key or other operating device, which latter is adapted to project through the usual slot in the side of the shell.

The primary object of this invention is to provide improved means for detachably connecting the shell and cap in any of their rotative relative positions, whereby the shell can be properly turned about its axis to dispose its key slot at any point about the periphery of the cap to receive the operating key without the necessity of making other adjustments heretofore found necessary to secure a proper alignment with the socket key. This is of special advantage in cases where the key of the socket must extend through a slot in an ornamental husk or other support.

An equally important object of the invention is to construct the interengaging fastener means of the cap and shell with inclined or undercut edges so as to absolutely prevent accidental separation of the cap and shell when assembled.

Other objects and advantages of the invention will become apparent during the course of the following description.

In the accompanying drawings forming a part of the application, and wherein like numerals are employed to designate like parts throughout the several views,

Figure 1 is a perspective view of the socket casing with the cap and shell disconnected.

Figure 2 is a longitudinal section through the assembled cap and shell.

Figure 3 is an enlarged transverse section through the same taken on the line 3—3 of Figure 2.

Figure 4 is an enlarged longitudinal fragmentary section of the fastening means, and

Figure 5 is an enlarged fragmentary view

showing an elevation of the interlocking means of the shell.

Referring now more particularly to the drawings, the numeral 6 designates the cap of the socket casing having the well known form of attaching nipple 7, by which the socket and casing are supported from an electrical conductor conduit or other support. This cap is provided with an annular depending flange or skirt 8 which is provided with a series of symmetrically arranged narrow vertical slots 9 arranged equidistant from each other around the entire circumference of the flange. These slots are spaced from one another a distance equal to the distance between cooperating interlocking means on a cylindrical, resilient, flexible socket shell 10, as will now be more fully described.

One end of this shell 10 is enlarged as at 11 to telescopically fit within the depending flange 8 of the cap in the well known manner. The inner or upper edge 12 of the shell is disposed in a plane perpendicular to the axis thereof, or in other words is square to the axis of the shell. Extending from this edge and into the enlarged portion 11 of the shell is the usual socket key slot 13, through which the key or other actuating device of the socket extends when the casing is associated therewith.

The intermediate portion of the shell 10 is provided with a shoulder 14 and at a point adjacent its outer end with a bead 15 below which the outer end of the shell is provided with a pressed thread 16.

To cooperate with the slots 9 of the cap for detachably connecting the shell and cap, two pairs of wings or catches 17 are provided on the exterior of the shell adjacent the edge 12 at diametrically opposite points. These wings 17 extend outwardly and radially of the shell and each pair of wings are spaced apart a distance corresponding to the distance between each two slots 9 of the cap. This coupled with the fact that the other pair of wings are arranged at a diametrically opposite point, and the fact that the spacing of the slots 9 circumferentially of the cap is uniform, it is obvious that the

wings 17 of both pairs will be positioned to register with the pairs of slots 9 in practically every rotative position of the shell with respect to the cap.

A very important feature of the present invention is to prevent the wings from accidentally pulling out of the slots 9 of the cap when the shell and cap are stressed or pulled apart longitudinally, such as when there is an excessively heavy weight suspended or supported from the shell portion of the casing. This is effectively accomplished by inclining the lower edges of the wings 17 upwardly and inwardly of the shell, so that they are in effect undercut to hook over the lower edges of the slots 9 in the cap and effectively prevent any accidental longitudinal separation or parting of the cap and shell when assembled and in use.

This object is accomplished in the present illustration of the invention by punching out the wings 17 from the shell to form integral parts thereof. The formation of each wing is accomplished by cutting the shell below the upper edge 12 thereof along a slightly curved line 18 substantially longitudinally of the shell down to a point determining the length of a wing 17. At this point, the cut is extended as at 19 at an acute angle to the cut 18 to incline it at an angle to the upper edge 12 of the shell. This defines the configuration of each wing 17, which is then pressed or bent outwardly of the shell along lines paralleling the axis thereof until they extend substantially radially as shown. The two side faces of each wing are parallel and, of course, extend radially from the shell and are also parallel to the two side walls of the slots 9 to abut therewith and limit relative rotary movement of the shell and cap in both directions. The cut 18 provides each wing with a curved upper surface which acts as a cam and presses that portion of the flange 8 immediately adjacent the wing outwardly, and that portion of the shell adjacent the wing inwardly when the end of the shell is slipped into the flange 8 of the cap. The inclined cut 19 provides each wing with an upwardly and inwardly inclined lower edge 20, as best seen in Figure 4, and forms each wing into a bill shape so that its lower edge will hook over the lower edge of the registering slot 9 of the cap when the shell and cap are pushed together for interlocking engagement. Due to the fact that the upper cam surface of each wing merges into or meets the inclined lower edge 20 at an acute angle, each wing is of pointed or bill-shaped configuration. Consequently, the weight of any ornaments or the like suspended by the shell will not cause the latter to become accidentally disengaged from the cap.

It will be noted that one pair of the wings 17 on the shell are provided adjacent one

edge of the key slot 13 where the shell can be most easily flexed inwardly to cause these wings to move inwardly and disengage from their coacting pair of slots 9. Of course, the shell adjacent the pair of wings at the point diametrically opposite the wings near the key slot 13 may be flexed inwardly to cause this pair of wings to disengage from its slots. When the shell is flexed inwardly adjacent either pair of interlocking wings, causing inward movement of the latter, their lower inclined edges ride upon the lower edges of the slots 9 and tend to draw the shell at this point slightly upwardly, it being noted that room for this slight longitudinal inward movement of the shell relative to the cap is permissible by reason of the fact that the inner edge 12 of the shell is spaced slightly from the shoulder 21 where the flange 8 joins with the cap 6.

After having pressed one portion of the shell inwardly to cause one pair of wings to disengage from the slots, the other pair of wings are disengaged from their slots by slightly tilting the shell on its axis.

When the shell and cap are pushed together to assemble them, they are flexed so that the flange 8 of the cap is cammed over both pairs of wings simultaneously, and registration of the slots 9 of these wings permits the flange 8 to snap over the wings into close engagement with the periphery of the shell.

It will be noted that the slots 9 are very narrow, and are practically nothing more than vertical slits. Likewise, the wings 17 are very thin, being equal to the thickness of the material of the shell, and the width of the slots 9 being substantially equal to the thickness of the wings, prevents any excessive relative rotative movement between the cap and shell when connected.

It is to be understood that various changes in the shape, size and arrangement of parts may be resorted to without departing from the scope of the appended claims.

I claim:

1. The combination with a two part lamp socket casing consisting of a flexible shell and a cap, said cap having a depending annular flange provided with a series of narrow vertical slots arranged symmetrically around the circumference of said flange, and said shell having pairs of wings struck out from the body of the same at diametrically opposite points and bent outwardly along lines paralleling the axis of the shell, both of said wings having flat parallel side faces extending radially from the shell body and being formed with outer edges having identically the same outline, whereby to support the cap with the sides of said slots parallel with the side faces of said wings as the cap is being mounted upon

said body to assure accurate registration of said wings with said slots.

2. A socket shell having an open top and having formed in its wall adjacent said top a plurality of openings, the portions of the shell removed from the openings being right angularly bent outwardly to form substantially radially projecting wings, each of said wings having flat parallel side faces extending radially from the shell body and being formed with two free edges, one of said edges extending on a continuous arc from the shell body outwardly and downwardly to the other edge, said other edge forming the wing bottom, said wing bottom meeting said arcuate edge at a sharp corner and extending inwardly from said corner to the shell body at an acute inclination to said body in the direction of its open top, and a cap for said shell having engaging means for said wings.

3. A socket shell having an open top and having formed in its wall adjacent said top a plurality of openings, the portions of the shell removed from the openings being right angularly bent outwardly to form substantially radially projecting wings, each of said wings having flat parallel side faces extending radially from the shell body and being formed with two free edges, one of said edges extending on a continuous arc from the shell body out and down to the other edge, said other edge forming the wing bottom, said wing bottom meeting said arcuate edge at a sharp corner, and extended inwardly from said corner to the shell body at an acute inclination to the body in the direction of its open top, and a cap for said shell having a series of narrow slots arranged around the circumference thereof to receive a pair of said wings in any relative rotary position of the shell with respect to said cap.

In testimony whereof I have hereunto set my hand.

JOHN WEBER.
